UNITED STATES PATENT OFFICE.

LEWIS PATTERSON, OF TERRE HAUTE, INDIANA.

MACHINE FOR MAKING HOOK-HEADED NAILS AND SPIKES.

SPECIFICATION forming part of Letters Patent No. 224,471, dated February 10, 1880.

Application filed January 23, 1879.

To all whom it may concern:

Be it known that I, LEWIS PATTERSON, of Terra Haute, in the county of Vigo and State of Indiana, have invented a new and valuable Improvement in Hook-Head Nail and Spike Machines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a top view of my invention. Fig. 2 is a side view thereof. Fig. 3 is an end view of the same. Figs. 4, 5, and 6 are details.

This invention has relation to improvements in machines for making nails and spikes with hook-heads; and it consists in the construction and novel arrangement of the vertically-adjustable cutting-lever and its journal-boxes, the double cam-shaft, and in connection therewith the gripping-lever and bending-bar, the open header-slide, and the wedge-cam on the short end of the cutting-lever, all as hereinafter fully shown and described.

In the accompanying drawings, the letter A designates the frame of the machine, the sides of which are connected by strong transverse beams B, B', and B''. The side bars of the frame are formed with raised cheek-blocks or elevations C, which are vertically slotted to receive the journal-boxes a, in which the journals a' of the cutting-lever L have their bearings. This lever extends in arched form across the frame, and is provided at one end with a power-arm, c', extending to the pitman of the crank-wheel c of the main driving-shaft d.

The journal-boxes a of the cutting-lever are adjustable in the slots of the cheek-blocks, in order that a slight change in the line of bearing of the knife-edge may be made, upon requirement, to cut the work thicker or thinner on the bed-die side, according to the character of the nails desired. For instance, it being premised that the nail-plate is fed to the machine at or at about an angle of forty-five degrees to the horizontal plane, which renders the cutting comparatively easy and lessens the jar upon the plate, and that the cutting-knife

in lever L vibrates in an arc of a circle with its center below the point where said knife meets the bed or fixed knife, it will be clear that said knife cuts more of the top side of the nail-plate than of its under side, and the bed-die side of the blank cut off will be narrower than the upper or moving die side thereof. The said blank will consequently not be square, but will have two converging faces, being of the form of a truncated wedge. This irregularity is in great measure overcome by lowering the outer end of the nail-plate by means of an adjustable support, upon which it rests, in the case of ordinary cut nails or spikes; but in hook-head nails it is of the last importance to have the blanks as nearly square crosswise as it is possible to make them. To do this the centers of vibration of the lever L must be raised in order to cause the cutting-knife to descend upon the nail-plate at right angles. Thus the blank will be square, or nearly so, in cross-section, and the adjustment of the centers of vibration of lever L must vary according to the thickness of the nail-plate.

In cutting hook-head clinch-nails the plates of which are three-sixteenths of an inch thick, lever L would be adjusted on its centers to shear a square blank; but this adjustment would not serve in cutting railroad-spikes, which are three-eighths of an inch thick, as they would not be square. The centers of lever L must therefore be still further raised.

The lever L carries a tool-holder, D', for the cutter, and in front thereof, on the front transverse beam, B, is the stationary tool-holder D, designed to receive the back piece, n, the bed-die l, and the bed-knife.

Depending from the under sides of the side bars of the frame are the broad hangers or cheeks Y, in which are seated the journals of the right-angular gripping-lever M, extending in arched form across the machine under the main body of the cutting-lever, and having a central upward projection, forming its operating or gripping end, from which extends backward, nearly horizontally from the bed-die, the power-arm d'', which is operated by means of a cam, d', on the driving-shaft d, the top of which is level with the bed-die, and which, at each revolution of said shaft, raises said power-arm and brings the operating end toward the

bed-die. The return movement of the gripping-lever to release the work is effected by the spring *f*, which is attached at one end to the frame of the machine, and at the other end 5 connected to said power-arm. The gripping-lever is thereby enabled to alternately seize and release the nail-blank.

N represents the bending-bar, arranged alongside the arm *d*² of the gripping-lever, and 10 extending through a slotted guide, *f'*, on the middle transverse bar, *B'*. This bending-bar extends over the driving-shaft, and is provided in front and rear of said shaft with lugs *f*², between which work the cam-projections *g* on 15 the shaft *d* in such a manner that they engage said lugs *g*, and, by a quick movement, thrust the bending-bar backward and forward in advance of the gripping and releasing movements of the gripping-lever; or the backward movement of the bending-bar may be given by 20 means of a retracting-spring. The forward end of the bar *N* extends alongside the gripping-die of the gripping-lever, which is wider than the bed-die *l*, and serves to bend the end of 25 the blank over the bed-die in hook form, this hooked end being afterward flattened or headed by the transversely-operating header *P*. The header is designed to be of such form as may be required in shaping the head, and is seated 30 in the open recess or seat of a U-shaped holder, *P'*, the base of which is of dovetail form and slides in ways *F* secured to the adjustable guide-plate *O*. These ways are arranged cross-wise of the frame, and the header is thrust 35 transversely against the hooked end of the nail-blank by means of a wedge-cam, *v*, on a

short forward arm or projection of the cutting-lever *L*, coming into action and operating the holder as the cutting-lever rises after having finished severing the nail-blank from the nail-plate. The header seat or holder is retracted 40 by means of a spring, *S*.

The material fed to this machine should be of good quality and at a red heat.

The bending-bar may be removed, if necessary, and the machine operated as a plain header. 45

Having described this invention, what I claim, and desire to secure by Letters Patent, is— 50

The hook-head nail-machine, having in rear the cam-shaft *d*, carrying the wheel *c*, cam *d'*, and cam-projections *g*, and in connection therewith the transverse cutting-lever *L*, provided with adjustable journal-boxes *a'*, a rear power-arm, *c'*, connected by a pitman to said wheel, and a forward projection having a wedge-shaped cam, *v*, in combination with the right-angular gripping-lever *M*, the bending-bar *N*, having the lugs *f*², the adjustable guide-plate 60 *O*, the transverse header-holder *P'*, engaging with said wedge-shaped cam, and the retracting-springs *S* and *f*, substantially as shown and described. 55

In testimony that I claim the above I have 65 hereunto subscribed my name in the presence of two witnesses.

LEWIS PATTERSON.
